WELL PUMPING APPARATUS

John M. Courtney, Vivian, La.

Application May 27, 1941, Serial No. 395,328

1 Claim. (Cl. 103—220)

The invention relates to well pumping mechanism and more particularly to the structure through which liquid is led to a pump at the bottom of a well. It has particular application to oil wells in which both oil and gas are present but can be applied to any type of well.

In most oil wells, because of their depth the pumping mechanism must be located at the bottom of the well rather than at the surface and it is particularly desirable to protect this mechanism against gas locks and sediment which would erode the pump mechanism. To this end many types of construction have been suggested for the purpose of eliminating gas and sediment from the oil before it reaches the pump. Some of these have been unsatisfactory because of their complexity and others because they were unable to satisfactorily separate out the gas and sediment from the oil.

The present device has the advantage of a very simple construction and yet is very efficient in its separation of the gas and the sediment from the oil. It provides a constant reservoir of relatively gas free oil that effectively prevents the pump from sucking in quantities of gas and thus becoming gas locked. At the same time it provides satisfactorily for the removal of sediment and thus greatly reduces any pump wear that would otherwise be caused by sediment.

To reach the pump, the oil, which quite often contains considerable quantities of gas, passes into a chamber of such dimensions that it will hold a quantity of oil sufficient to supply the pump for a number of oscillations. It is permitted to remain in this chamber and is subjected to an oscillatory pressure variation due to the action of the pump for a sufficient period of time to liberate a large portion of the free gas contained therein. The gas is allowed to escape out of the chamber and back into the surrounding formation and the liquid, oil in most cases, is drawn through one or more restricted openings into a second chamber where any sediment in it is permitted to settle to the bottom of the chamber. From the top of this chamber the oil or other liquid passes to the pump and is lifted to the surface of the earth.

Further details and advantages of this construction will be apparent from a consideration of the following detailed description of the preferred embodiment thereof and from the accompanying drawing.

In the drawing the single figure illustrates in vertical cross-section the preferred embodiment of the device of this invention.

As illustrated this device consists of a pump tube 10 in which is positioned a pump piston 11 reciprocated from the surface of the earth by a pump rod 12. The pump piston 11 carries a traveling valve 13 and a stationary valve 14 is located below it in the pump tube. At the bottom of tube 10, and connected thereto by a short intermediate tube 10a, is a settling chamber 15 defined by a hollow cylindrical member 16 and 10 a cup shaped member 17 threaded into the lower end thereof. Above the settling chamber and surrounding the pump tube is a gas separation chamber 18 defined by the top of the cylindrical member 16, a piece of tubing 19 larger than the 15 pump tube and an annulus 20 sealing the top end of this larger tube to the pump tube.

Liquid and gas are admitted to the separating chamber 18 through openings 21 partway up the side of the separating chamber. Any gas that 20 separates out of the fluid in the chamber is permitted to escape through openings 22 nearer the top of the chamber.

Communication between the separating chamber and the settling chamber is had through 25 openings 23 of restricted size in the cylindrical member 16. These openings connect the bottom of the separating chamber directly to the top of the settling chamber.

Preferably the capacity of the gas separating 30 chamber is such that it will hold approximately two and one half times the amount of liquid that the pump will move in a single stroke. The gas escape slot 22 is about three inches below the top end of the gas separating chamber. The size of 35 the slots through which oil and gas enter and gas leaves the separating chamber and the size of the openings between the separating chamber and the settling chamber and the number of these openings depend upon the diameter of the 40 well bore and the capacity of the pump.

Experience has shown that when the size of 45 these openings is properly adjusted for a particular pumping job, the gas is very efficiently separated from the oil, the sediment separates out very satisfactorily, the gas at the top of the separating chamber has a surge chamber effect which causes the pump to operate more efficiently, trouble with gas locks is eliminated, and the 50 pump serves longer without replacement because of the elimination of these disturbing and wearing factors.

It is to be understood that numerous modifications of the design illustrated may be made 55 within the skill of those familiar with the art

without departing from the spirit of this invention.

I claim:

In a device of the type described, a pump tube, a reciprocating pump disposed substantially at the lower end thereof, a settling chamber disposed below said pump tube and in unrestricted communication therewith, a cylindrical surge chamber surrounding said pump tube, a series of vertically elongated openings in the outer wall

of said surge chamber for the admission of oil and the escape of gas, said openings being positioned sufficiently below the top of said surge chamber so that a quantity of gas will be trapped in the chamber above the openings to make the chamber function as a surge chamber, and means establishing restricted communication between the bottom of said surge chamber and said settling chamber.
